UNITED STATES PATENT OFFICE.

JOHN JAMES MARSHALL, OF LEEDS, ENGLAND, ASSIGNOR TO JOHN POTTS BROWN, OF MINNEAPOLIS, MINNESOTA, AND WILLIAM HENRY SEWARD AND EDWIN POTTER CARPENTER, OF LONDON, ENGLAND.

AUTOMATIC WEIGHING-MACHINE.

SPECIFICATION forming part of Letters Patent No. 680,160, dated August 6, 1901.

Application filed March 11, 1901. Serial No. 50,710. (No model.)

To all whom it may concern:

Be it known that I, JOHN JAMES MARSHALL, grocer, a subject of the King of Great Britain, residing at 9 Branch road, Armley, Leeds, England, have invented certain new and useful Improvements in Apparatus for Automatically Weighing Granular Substances, such as Sugar, Rice, and the Like, of which the following is a specification.

10 My invention relates to a machine for automatically weighing sugar or the like or other granular substances into parcels of any given weight.

Referring to the drawings hereunto annexed, Figure 1 is a side elevation, partly in section, of my improved weighing-machine. Fig. 2 is a cross-section showing detached the mechanism employed for actuating the delivery-cut-off slides. Fig. 3 is an enlarged 20 front elevation of adjusting or compensating weight. Figs. 4 to 7 show, on an enlarged scale, slightly-modified arrangements of certain parts—viz., means for preventing or reducing vibration, as well as noise, from the impact of the rod or slide K—Fig. 4 being a “local” view of part of the two sliding rods K and L, and Fig. 5 a plain view of the rod K, all the parts above same having been removed. Fig. 6 is a local view of the rear end 25 of the said two rods K and L, showing an alternative arrangement. Fig. 7 is a plan view of Fig. 6.

Referring more particularly to Figs. 1 to 3, in constructing the machine I employ a feed-hopper A upon a suitable frame B for the reception of the sugar or other material to be weighed. The said hopper preferably is funnel-shaped and terminates at its lower end in a circular opening. Beneath the hopper 35 is placed the weighing apparatus, which consists of a scale-pan C upon a balance-lever or scale-beam D in suitable bearings, and with a preferably fixed weight E, fixed stops H and J, and a suitable adjusting eccentric weight F. The bags or other receptacles (into which the granular material is to be discharged from the hopper A) are placed one at a time upon the scale-pan C, which is provided with an arm G for supporting them. Near the lower opening of the feed-hopper A are two horizontal

slide-rods K L, working one above the other in suitable bearings in a detachable bracket M. Toward the ends of the said rods K L are spiral springs N N², the said springs having a tendency to push the rods forward toward the 55 hopper-outlet. Upon the upper rod K is a projecting incline or runner P, which engages with a similar incline or runner R, carried by a pivoted lever S, having a supporting-link S². The runners P and R are held in contact, 60 so as to resist the action of the spring N, by means of vertical rods T T, (see Fig. 2,) which bear against the top of the lever S and pass down under the scale-beam D, (at its weighted end,) the said rods T T terminating in a stirrup U, having a fixed guide V near the fixed stop H. To regulate the resistance or drag of the runner R on the upper rod K, I preferably employ the coiled spring W, with screw adjustment X, the said spring being placed over 65 the lever S and having a loop bearing on the end over the runner R. The rod K terminates in a tapered or funnel opening A' of smaller diameter than the hopper-outlet, so that when pushed forward under the hopper it decreases 70 the delivery from the hopper. The rod L terminates in a slide or cut-off B', which when pushed forward under the tapered opening A' closes it and stops the delivery from the hopper A. Suitable shields C' D' E' may be 75 provided to prevent loss of sugar, &c., at the hopper-outlet. As shown in the drawings, the shield C' is carried by the rod L and the shield D' is mounted upon and moves with the upper rod K. The shield E' is stationary 80 and may be secured to the hopper or any other stationary part of the device. The rod L has a pin F', which engages with an inclined catch G', carried by a pivoted lever H', working in a guide H². Connected to the said lever H' is a vertical rod J', which passes downward through the upper part of the stirrup U (which acts as a guide for same) and terminates immediately over the scale-beam D. A regulating-screw K' is provided for adjusting 85 the catch G', so as to make it more or less sensitive. The adjusting-weight F bears against a vertical rod L' on the scale-pan C and has a hook or finger M', which engages 90 with an incline P' on the rod L. (See Figs. 100

1 and 3.) The rods K and L are provided with thumb-pieces or knobs N' R', the upper knob N' having a catch S', which operates the lower knob R'. Suitable stops T' T' T' are provided to limit the movement of the rods K and L.

The action of the machine is as follows: The sugar or other substance to be weighed passes into the hopper A and from thence into the bags placed upon the scale-pan C. When the weight of the sugar or other material in the bag has almost reached the proper weight, the weight of the weighted end of the balance-lever upon the bottom of the stirrup U diminishes, allowing the rods T T' to rise, removing the pressure from the pivoted lever S. The spring N upon the top rod K then pushes said rod forward under the hopper, decreasing the opening and reducing the delivery from said hopper. When the scale-pan C contains the required weight, the scale-beam D rises, coming into contact with and lifting the rod J'. This releases the pin F' and allows the rod L to be now also shot forward, so closing the hopper-outlet. At the same time the incline P' on the rod L lifts the eccentric weight F clear of the rod L', allowing the scale-beam D to ride at a balance, and so giving a test as to the correct weight of each parcel.

The working parts of the machine, which are all attached to the bracket M and are therefore easily removable, are or may be protected by suitable casings or covers attached in any suitable manner. The frame B is preferably supported from the stand or bed U' by means of four pillars V'.

Referring to Figs. 4 and 5, Y is a stop, consisting of an arm or bracket or stop-piece 40 screwed to the side of the slide-rod K and provided with a socket or otherwise formed or adapted to receive and hold therein a pad or block or buffer or cushion Z, of rubber or other suitable elastic substance or other suitable material adapted to deaden or reduce

the shock or shaking and noise which would otherwise be occasioned when said slide-rod K (upon being liberated and shot forward) comes into contact with the fixed part of the frame or bracket M, through which said rods slide, just at the moment when the said slide-rod K has reached the limit of its movement to effect the partial cut-off, as aforesaid.

Referring to Figs. 6 and 7, in this case the rear end of the slide-rod K is provided with a laterally-extending arm, stop, or extension Y', adapted to carry and hold therein the rubber or other suitable buffer Z', which consequently will strike against the fixed part M² of the frame M, as indicated in dotted lines in Fig. 7 of the drawings hereunto annexed.

Having now described my invention, what I claim as new, and desire to secure by Letters Patent of the United States, is—

In a machine for automatically weighing granular substances, the combination with a weighted scale-beam, a scale-pan carried thereby, and a feed-hopper mounted above said scale-pan; of a reciprocating rod, means carried by said rod for reducing the delivery from said hopper when reciprocated, a spring for reciprocating said rod, a stop on said rod adapted to engage with a fixed portion of the frame, an elastic buffer interposed between 75 said stop and portion for reducing the shock of said rod when reciprocated, means operated by said scale-beam for automatically releasing said reciprocating rod, and a second rod for cutting off the delivery from said hopper, also adapted to be operated automatically by said scale-beam, substantially as described.

In witness whereof I have hereunto set my hand in presence of two witnesses.

JOHN JAMES MARSHALL.
